Edward D. Pickett

UNITED STATES PATENT OFFICE.

EDWARD PICKETT, OF GARLAND, KANSAS.

FOLDING GATE.

SPECIFICATION forming part of Letters Patent No. 508,750, dated November 14, 1893.

Application filed April 22, 1893. Serial No. 471,527. (No model.)

To all whom it may concern:

Be it known that I, EDWARD PICKETT, a citizen of the United States, residing at Garland, in the county of Bourbon and State of Kansas, have invented certain new and useful Improvements in Gates, of which the following is a specification.

This invention relates to gates, and it consists in the novel construction and combination of the parts hereinafter fully described and claimed.

In the drawings: Figure 1 is a front view of the gate. Fig. 2 is a section, taken on the line $\alpha\alpha$ in Fig. 1. Fig. 3 is a plan view of the gate, from above.

A and A' are the two gate posts. The post A has brackets a secured to it for supporting the gate at one end. One end of the gate is connected to the brackets a , and the other end 20 of the gate, when closed, is connected to the post A' by any approved form of catch or fastening, such as the hook a' .

When the gate is intended to be used merely as a folding gate, one end of it is secured to the brackets a , but if desired its end 25 may be pivoted to the brackets a in any approved manner, so that it may be opened and shut by turning it on its pivots as well as by folding it back.

30 B is the vertical end bar of the gate which is pivoted in the brackets a . B' is the similar vertical bar at the other end of the gate. C are vertical intermediate bars. D D' are crossed bars pivoted on the upper and lower ends of each of the bars C.

35 E E' are bars pivoted on the upper and lower ends of the bars B B'. The meeting ends of the bars D D' between the bars C, and the bars E E', are pivoted on the vertical bars 40 F, each bar F connecting a bar D or E with a bar D' or E' at the top and at the bottom of the gate.

G are vertical bars secured to the horizontal bars D' and E' between the bars B B' and C, and the bars F so as to prevent animals 45 from passing between the said bars B B' and C when the gate is closed.

Each bar B B' and C has a block H on its upper end.

I are inclined bars pivoted to the blocks H 50 by the pins i and having their upper ends pivotally connected together in pairs by the pins i' .

I' are distance pieces between the upper ends of the bars I for the pins i' to pass 55 through.

When the gate is folded back, the horizontal bars are spread out and pushed together as indicated by the dotted lines k in Fig. 3, and the inclined bars I are simultaneously 60 raised into an almost vertical position and are pushed together as indicated by the dotted lines k' in Fig. 1.

What I claim is—

In a gate, the combination, with the vertical end bars B B', and the intermediate vertical bars C; of the pairs of crossed horizontal bars pivoted on the upper and lower ends of the said vertical bars, the vertical bars F pivotally connecting the ends of the said horizontal bars, the blocks on the upper ends of the bars B, B' and C, and the inclined bars I having their lower ends pivoted to the said blocks and having their upper ends pivotally connected together in pairs, substantially as 75 shown and described.

Witness my hand and seal this 17th day of January, A. D. 1893.

EDWARD PICKETT. [L. S.]
